Specification of Letters Patent.

Patented May 7, 1918.

Application filed April 21, 1915. Serial No. 22,730.

To all whom it may concern:

Be it known that we, RICHARD H. PIETZSCH, and ROBERT P. NICHOLS, citizens of the United States, of the city and county of Philadelphia, State of Pennsylvania, have invented new and useful Improvements in Motion-Picture Apparatus, of which the following is a specification.

Our invention relates to kinetographic projecting or exposure making apparatus wherein is used a film or other picture unit support in which the picture units in the kinetographic series are disposed in longitudinally neighboring rows extending transversely of the film.

It is the object of our invention to decrease the weight and therefore the inertia of the moving parts, and particularly the transversely moving parts, which control or operate the film. As contributing to this end we provide film storage and film rewinding spools or reels which are stationary in the sense that they do not move with the parts which move the film transversely. And in this relation we arrange the film in a flexible loop in advance of and after its engagement by the operating or controlling means, whereby the transverse movements of the film are accompanied by lateral flexures of the film loops.

It is a further object of our invention to improve the mechanism for controlling the lateral and transverse feeding of the film to the end that such mechanism shall be substantially noiseless and smooth in operation.

Our invention resides in these and further features of arrangement and combination hereinafter described and claimed.

For an illustration of one of many forms our invention may take reference is to be had in the accompanying drawings, in which:

Figure 1 is a vertical sectional view, some parts in elevation, on the line 1—1 of Fig. 4.

Fig. 2 is a vertical transverse sectional view, some parts in elevation, taken on the line 2—2 of Fig. 1.

Fig. 3 is a transverse vertical sectional view, some parts in elevation, taken on the line 3—3 of Fig. 1.

Fig. 4 is a vertical sectional view, parts in elevation, taken on the line 4—4 of Fig. 1.

Fig. 5 is a fragmentary side elevational view, some parts in vertical section, of parts shown in Fig. 4.

Fig. 6 is a fragmentary front elevational view, partly in vertical section, taken on the line 6—6 of Fig. 4.

Fig. 7 is an enlarged fragmentary sectional view taken on the line 7—7 of Fig. 6.

Fig. 8 is a plan view of a part of a film.

Fig. 9 is an enlarged edge view of a film feeding wheel.

Fig. 10 is a section, partly in elevation, on line 10—10 of Fig. 1.

Fig. 11 is a plan view of part of the control mechanism.

Fig. 12 is a plan view, partly in section, showing the pressure plate control.

Referring to the drawings, B is a suitable camera or projector box having the front wall *a* and the rear wall *b*.

Within the box B is the plate or wall *c* held in fixed position with respect to the ribs or projections *d* on the box B, light proofing material *e* intervening between the projections *d* and the plate *c*. The plate *c* forms one wall of a casing *f* having the lower wall *g* resting against or secured to the bottom of the box B. Between the plates *a* and *c* is disposed the rotary shutter *h* having the arc shaped openings indicated at *j*, Fig. 1, which during rotation of the shutter allows for a predetermined suitable time free light passage, the openings *j* rotating before the lens *k*.

With its axis in the optical axis of the lens *k* and of the instrument is a chamber *m* carried by the plate *c* and terminating at its inner end in the smaller tubular projection *n*. The shutter *h* is driven by the beveled gear *o* journaled in the plate *c* and meshing with the driving beveled gear *p* secured upon the shaft *q* to which is secured the pinion *r* meshing with the gear *s* driven by the hand crank *t* through the shaft *u*.

The gear *s* drives also the pinion *v* secured upon shaft *w* upon which are secured the variable pitch screws *x*. The screws *x* have variably pitched screw threads of which the channels *y* have throughout the greater portion of 100 a circumference no pitch longitudinally, neighboring channels *y* being connected by

the inclined or curved channel portions z which are the only portions having a longitudinal pitch. At one end of each of the variably pitched channels y it decreases in depth as indicated by the bottom surface a^1 which rises substantially to the top of the channel y .

The beginning of the rise a^1 is substantially at the maximum of the lateral deflection b^1 which is flanked by the members c^1 and d^1 of greater radial depth than the screw x , that is, the flanking members c^1 and d^1 are built up upon the periphery of the screw x to insure sufficient depth of slot for purposes later described. See Fig. 10. At the opposite end of each screw slot y there is a lateral deflection e^1 terminating in the enlargements f^1 for the easy reception of the pins later referred to. Upon the unpitched parts of the screw x are outwardly extending locking ribs g^1 .

A plate n^1 having a slot r^1, o^1, q^1, p^1, s^1 is disposed above the wall j^1 . Its function will appear later.

Disposed parallel with the shaft w is the longitudinally movable and rotatable shaft h^1 which passes through the wall i^1 of the casing. Secured upon shaft h^1 is the pin wheel j^1 carrying at its one end a circumferential series of equally spaced pins k^1 and at its other end a similar series m^1 , the pins of one series at one end being staggered or alternated in angular position with the pins at the other end, whereby a pin k^1 and a pin m^1 will not be simultaneously in mesh with their respective screw slots y, y and thereby become locked.

Carried on the inside of the casing f is an arc shaped plate n^1 having therein the parallel slots o^1 and p^1 joined by the curved slot q^1 and having the terminal outlets r^1 and s^1 , Fig. 11. With these slots coöperate the pins m^1 as hereinafter described.

Secured to the shaft h^1 to move longitudinally and rotatably therewith is the film feeding wheel t^1 having the teeth u^1 for engaging a single row of perforations in a film, the wheel t^1 being shown in edge view in Fig. 9 on larger scale. The shaft h^1 is hollow and slides longitudinally upon and rotates upon the bar v^1 supported at its outer end in the bracket w^1 . The film guiding or supporting frame or plate x^1 is movable transversely upon the stationary bar or shaft y^1 and is prevented from rotating thereon by the lug z^1 which travels longitudinally in a slot in the longitudinally extending member a^2 carried by the wall c .

The frame x^1 is carried backwardly and forwardly transversely by the shaft h^1 by being confined between the collar b^2 , Fig. 1, and the extended hub c^2 of the sprocket wheel t^1 .

As seen in Figs. 6 and 7, the frame x^1 has

pivoted thereto on the screws d^2 the eccentrics or cams e^2 which are drawn toward each other by the spring f^2 . The lower edges of these cams e^2 engage plates g^2 disposed in openings in the circular bearings h^2 of the member x^1 upon the shaft y^1 . The bearing h^2 is cut away as indicated at i^2 , Fig. 7, so that there are formed points or edges j^2 . The tension of the spring f^2 urges the cams e^2 in such direction as to press the members g^2 against the pin or shaft y^1 , thus raising the frame x^1 and its bearing h^2 against the under side of the shaft y^1 , so that the sides of the bearings around to the points j^2 engage the shaft y^1 , giving a 3-point bearing. This structure steadies the movement of the member x^1 and prevents any play between the shaft y^1 and its bearing.

Between the bearing portions h^2 of the frame x^1 are swung the arms k^2 pivoted upon the shaft y^1 and having pivoted in their outer ends the pressure roller m^2 for pressing the film against the feed sprocket t^1 .

In the frame x^1 is formed the transversely extending slot n^2 into which the tubular projection n on chamber m extends, as best seen in Fig. 5. The slot n^2 extends only partially through the plate x^1 . Within the slot n^2 , however, are the rectangular openings o^2 extending through member x^1 and between which are the ribs p^2 . These rectangular openings o^2 are substantially the shape and size of the picture units upon the film, and there are as many of these openings o^2 as there are picture units in a row on the film, the ribs p^2 registering with the spaces between picture units.

Pivoted on the vertical pivot screws or pins q^2 carried by the lugs or ears r^2 on the frame x^1 is the yoke member s^2 carrying at its outer ends the vertical pivots t^2 upon which is pivoted the pressure plate v^2 having rectangular apertures o^2 with intervening ribs p^2 registering respectively with the apertures o^2 and ribs p^2 in the plate x^1 . A plunger x^2 , Figs. 1, 4, 5 and 12, is carried by the frame x^1 and is pressed outwardly by the spring y^2 , Fig. 12, against the extension z^2 of the yoke s^2 to the rear of the pivot q^2 . This thrust by the plunger x^2 holds the pressure plate v^2 toward the frame x^1 , the pressure plate v^2 pressing its ribs p^2 against the film. As will be noted from Fig. 12, if the yoke s^2 and the pressure plate v^2 be swung about the pivot q^2 in a counterclockwise direction, away from the frame x^1 , the corner or projection a^3 will ride under and past the plunger x^2 until the plunger x^2 engages the surface b^3 , whereby the plate v^2 and yoke s^2 will be held by spring pressure away from the plate x^1 to allow threading of the film through the machine. On the shaft or arbor c^3 supported in the lugs or ears d^3 on the frame x^1 is rotatable the film engaging

sprocket wheel e^3 similar to the wheel t^1 previously described. On the bracket f^3 carried by the frame x^1 are pivoted the arms g^3 carrying at their outer ends the pressure 5 roller h^3 .

On the wall i^1 or any other suitable stationary part are disposed the film reel in-closing boxes j^3 each having a cover k^3 to completely inclose the film in light proof

10 fashion when required. Near the upper box j^3 extends a shaft m^3 driven by gear n^3 , which is in turn driven by the gear o^3 , driven by the gear p^3 which is in turn driven by the pinion u^1 on shaft u which is directly 15 driven by the hand crank t . Secured upon the shaft m^3 is a film engaging and feeding sprocket q^3 similar to the previously described sprocket t^1 . And coöperating with the sprocket q^3 is the pressure roller r^3 carried in the outer end of arms s^3 pivoted at t^3 .

On the shaft v^3 , driven by the gear p^3 is secured the film take-up sprocket w^3 , Fig. 4, with which coöperates the pressure roller x^3 carried by the arms y^3 pivoted at z^3 .

25 Extending into the lower reel box j^3 is the shaft a^4 upon which is loosely journaled the gear b^4 , Fig. 3, meshing with and driven by the gear p^3 . On the shaft a^4 is a collar or washer c^4 pressed against the face of the 30 gear b^4 by the spring d^4 whereby the shaft a^4 is frictionally driven. When the cover z^3 of the lower film box j^3 is removed a film re-winding or receiving reel e^4 having the hub f^4 is slipped into the box j^3 as far as the 35 bead g^4 , the hub f^4 being centered upon the shaft a^4 . The reel e^4 has secured thereto a flange h^4 having slots j^4 adapted to receive the pin k^4 driven by the shaft a^4 , whereby the reel e^4 is driven by the shaft a^4 to re- 40 wind the film.

In Fig. 8 is illustrated the film F having thereon successive transversely extending rows of picture units numbered from 101 to 132 to indicate, by way of example, their 45 order of succession in a kinetographic series.

While the film is here shown as having four picture units per row it will be understood that our invention is not limited to this number, since a lesser number or a 50 greater number per row may be employed. Between the lateral edges of the film F are disposed in a longitudinal row the perforations m^4 in which engage the teeth or projections u^1 on the sprocket wheels t^1 , e^3 , q^3 , 55 and w^3 .

By thus using a single row of perforations and placing it at or near the middle of the film, the effects of lateral shrinkage of the film, due to development and drying, or any 60 other causes, are minimized, with the result that the picture units register with greater accuracy with the apertures o^2 and the optical system of the apparatus than in the

case of a film having a double row of perforations as is customary. 65

While in Fig. 8 we have shown the row of perforations m^4 at the middle of the film, the same may be to one side of the middle, in which case such location of the perforations will insure the film being threaded 70 through the apparatus with the proper side thereof toward the lens.

As shown the perforations m^4 are disposed at the intersections of the longitudinal and transverse divisions or joints o^4 and r^4 between picture units, whereby these perforations do not disfigure or interfere with the picture unit itself. 75

Fig. 8 shows these perforations m^4 occurring only once for two rows of picture units, 80 though it will be understood that there may be a perforation m^4 for each row or for other multiple of rows.

It will be noted also that the sides of the perforations m^4 , here shown quadrilateral 85 in form, are inclined with respect to the longitudinal axis of the film and that the teeth u^1 on the sprocket wheels are similarly shaped. The result is that as a tooth u^1 enters a perforation m^4 there is a wedging action which compels the film F to take such position transversely as to register exactly with the sides and angular edges of the teeth u^1 . This action upon the film F insures that it will run perfectly in a straight 90 line between the pressure plate v^2 and the plate x^1 , with the result that the film will have no play or motion laterally, but will always bring the picture units into exact 95 register with the optical axis. 100

While we have shown the teeth u^1 and apertures m^4 as quadrilateral in form, it will be understood that they may take other forms, for example, hexagonal; and the sides of the teeth and of the apertures need not be straight, but may be curved. Thus, for example, the apertures and teeth may be elliptical or oval in shape, or of any suitable shape whereby there will be the lateral wedging action between the teeth and the edges of the perforations to cause the film to track in a straight line or with accuracy. It will be understood further that the teeth on the feed sprocket need not have a form similar to or identical with the form of the perforations, so long as the wedging action takes place. For example, with perforations having converging inclined or curved sides there may be used on the feed sprocket circular or similar pins which in engaging the converging curved or inclined sides of the perforations will also perform 110 the wedging action. 115

While we prefer to use a single row of perforations in the film for effecting its 120 feeding, it will be understood that in addition 125

tion to such a single row of perforations we may employ in either or both lateral margins of the film or elsewhere one or more rows of perforations, for example of the ordinary type, with which may coöperate feed and take-up sprockets which may be used in lieu of the sprockets q^3 and w^3 , or either of them. By such arrangement there will be less wear and tear upon the edges of the 10 perforations in the single row, which may then be used solely or substantially solely for accurately determining lateral position or centering of the film.

As the film F passes over the sprocket 15 wheels referred to, the coöperating rollers press the same into proper engagement with the sprocket wheels. These sprocket wheels and pressure rollers have the laterally disposed circular ribs n^4 which register with 20 the marginal spaces o^4 , Fig. 8, between picture units of the film F, these spaces o^4 registering with the ribs p^2 on the plate x^1 and on the pressure plate v^2 . The pressure rollers are all spring pressed against their 25 coöperating sprockets, as by torsion springs, one of which is indicated at p^4 , Fig. 1.

The operation is as follows:

The pinion u^1 and gear s are rotated at substantially uniform speed by any suitable means, as the hand crank t . Accordingly the gear n^3 is driven at uniform speed, thereby driving the shaft m^3 and the sprocket wheel q^3 at uniform speed. Similarly, the gear p^3 drives the shaft v^3 , which 35 rotates the take-up sprocket w^3 at uniform speed.

The uniform rotation of the sprocket q^3 causes the film F to be uniformly unwound from the storage reel in the upper box j^3 , 40 the film passing over the sprocket q^3 and thence into a loose fold or loop L and thence between the pressure roller h^3 and the sprocket e^3 , thence from the right hand side of the sprocket wheel e^3 , as viewed in Figs. 45 4 and 5, downwardly between the ribs p^2 on the members x^1 and v^2 , thence over the main intermittent feed sprocket t^1 between the latter and the roller m^2 , thence into a loose fold or loop L^1 , thence over the take-up sprocket w^3 between the same and the pressure roller x^3 and thence into the lower box j^3 on to the reel e^4 on which the film is wound up, the shaft a^4 being frictionally 50 driven, so that there may be slippage between the shaft a^4 and its driving gear b^4 , whereby as more and more film is wound upon the reel e^4 the latter will make fewer and fewer revolutions in proportion to the 55 number of revolutions of the crank t .

60 It will accordingly be understood that the free folds or loops L and L^1 in the film F are disposed between the sprockets q^3 and w^3 , which do not move transversely with the frame x^1 . The result of this construction is 65 that the sprockets q^3 and w^3 and the boxes

j^3 and their film and reels need not move with the transversely moving frame x^1 , whereby the weight and therefore inertia of the transversely moving parts is greatly decreased, with the result that the apparatus 70 is the more easily operated, and operates more smoothly and with far less noise.

The variably pitched screw x rotates continuously and serves to impart to the frame x^1 intermittent transverse movement at the 75 ends of which the feed sprocket t^1 is rotated to step the film longitudinally a distance equal to the distance between centers of neighboring rows of picture units.

In the position shown in Fig. 1, the frame 80 x^1 is in position for exposure of the end picture unit of a row, as for example, picture unit 108, Fig. 8. Further rotation of the top of the member x , Fig. 1, toward the observer, will cause the roller pin m^1 to be deflected laterally toward b^1 carrying the pins m^1 to another of the ends s^1 of the slot p^1 of member n^1 . Simultaneously a pin k^1 at the other end of the wheel j^1 is opposite the entrance f^1 of the screw thread of the left 90 hand part of the member x . Further rotation of the member x causes the surface a^1 at the right end of the member x to rotate the pin m^1 to rotate the wheel j^1 , thereby entering the pin k^1 into the left hand screw 95 slot and simultaneously withdrawing a pin m^1 from the slot end s^1 and entering another pin m^1 into the slot r^1 , continued rotation causing the wheel j^1 to be shifted slightly toward the left to a position similar to that 100 indicated in Fig. 1, whereupon the frame x^1 is in position for exposure of the picture unit 109 at the right end of the next row, the partial rotation of wheel j^1 having rotated feed sprocket t^1 to feed the film F longitudinally one step. Continued rotation of the member x then intermittently shifts the wheel j^1 and therefore the frame x^1 in 105 intermittent steps toward the left by reason of engagement of a pin k^1 in the left hand screw slot y . Simultaneously the pin which entered the slot r^1 moves toward the left in the slot o^1 with these same intermittent movements, thus causing exposure in succession of the picture units 110, 111 and 112. 110 After unit 112 has been exposed the pin k^1 is shifted laterally at b^1 at the left end of the member x , and then moves backwardly again, but during such movements the part 115 a^1 rotates the pin k^1 , and simultaneously the pin in the slot o^1 has passed through the curved slot q^1 into the slot p^1 by a lateral and return movement combined with a rotary movement at the time a pin m^1 has entered at f^1 into the left end of the right hand 120 screw slot y .

In other words, the pin m^1 enters the member n^1 at the slot r^1 , passes stepwise toward the left through the slot o^1 , then by a lateral left hand and right hand movement 130

combined with a rotary movement passes from slot q^1 into slot p^1 , thence toward the right in the slot p^1 by step movements, caused by parts b^1 and a^1 at one end of screw member x , and finally out at slot s^1 at the time the second pin enters r^1 .

Each rotative movement of the wheel j^1 , at the end of the lateral movements, and during the extra lateral and return movement of the frame x^1 rotates the feed sprocket t^1 through an angle sufficient to step the film longitudinally a distance equal to the distance between centers of adjacent rows of picture units to bring the next row of picture units into operative position.

These lateral movements of the frame x^1 are permitted by the loops L and L^1 ; and the film continuously pulled out of the upper box j^3 by sprocket q^3 and continuously taken up by take-up sprocket w^3 and delivered to the rewinding reel in the lower box j^3 , is intermittently fed as to the part between loops L and L^1 by the sprocket t^1 which moves with the frame x^1 . Between the loops L and L^1 the film is engaged by the feed sprocket t^1 and the idler sprocket e^3 , the rotation of the latter by pull exerted on the film by sprocket t^1 being opposed by friction, whereby the film between the sprockets e^3 and t^1 is held stretched or taut, with the result that the engagement of the film by these sprockets e^3 and t^1 insures its accurate lateral positioning with respect to the optical axis or the means which move the film laterally.

Between transverse movements of the wheel j^1 it is locked against any transverse movement or oscillation by confinement between neighboring locking ribs g^1 on the member x ; and the longitudinal slots o^1 and p^1 in one or the other of which a pin is always confined during lateral movement of the frame x^1 positively locks the wheel j^1 against any rotative movement which in one direction would tend to pull the film F downwardly between plate x^1 or the pressure plate v^2 or in opposite direction would tend to loosen the film.

The rate of the continuous rotation of the shutter h is such that the slots or apertures j rotate in front of the lens k only while the frame x^1 is at rest.

By the apparatus described a continuously rotating cam or variably pitched screw imparts intermittent lateral and rotative movements to the shaft h^1 , which imparts intermittent lateral movements in both directions to the frame x^1 and intermittent rotative movements always in the same direction to the feed sprocket t^1 ; the film storage and rewinding reels are stationary in the sense that they do not move with the frame x^1 , and the same is true of the sprockets q^3 and w^3 , only the feed sprocket t^1 and the sprocket e^3 moving with the frame, t^1 pulling downwardly intermittently upon the film F .

against the opposition by the sprocket e^3 occasioned by the friction caused by the thrust of the end of the sprocket e^3 against the lug or ear d^3 caused by the spring q^4 , Fig. 6.

It will be understood that our invention herein claimed is not limited to the use of any particular structure of the film, and that while a film of the character herein described, having a single row of perforations or otherwise formed, may be used, films of any other forms, such as those having the usual double rows of perforations, may be employed.

What we claim is:

1. In kinetographic apparatus, the combination with film holding means, of a frame movable laterally with respect to said means, and a film held by said means and moved laterally by said frame.

2. In kinetographic apparatus, the combination with film holding means, of a frame movable laterally with respect to said means, a film held by said means and moved laterally by said frame, and means movable with said frame for feeding said film longitudinally.

3. In kinetographic apparatus, the combination with film holding means, of a frame movable laterally with respect to said means, a film held by said means and moved laterally by said frame, and means movable with said frame for intermittently feeding said film longitudinally.

4. In kinetographic apparatus, the combination with film holding means, of a frame movable laterally with respect to said means, a film held by said means and moved laterally by said frame, and means for moving said frame intermittently.

5. In kinetographic apparatus, the combination with film holding means, of a frame movable laterally with respect to said means, a film held by said means and moved laterally by said frame, means movable with said frame for feeding said film longitudinally, and means for moving said frame intermittently.

6. In kinetographic apparatus, the combination with film holding means, of a frame movable laterally with respect to said means, a film held by said means and moved laterally by said frame, means movable with said frame for intermittently feeding said film longitudinally, and means for moving said frame intermittently.

7. In kinetographic apparatus, the combination with a looped film, of film holding means with which one end of the loop communicates, and a frame movable laterally with respect to said means engaging said film at the other end of the loop.

8. In kinetographic apparatus, the combination with a looped film, of film holding means with which one end of the loop com-

municates, a frame movable laterally with respect to said means and engaging said film at the other end of the loop, and film feeding means engaging said film between said first 5 named end of said loop and said holding means.

9. In kinetographic apparatus, the combination with a looped film, of film holding means with which one end of the loop communicates, a frame movable laterally with respect to said means and engaging said film at the other end of the loop, and continuously 10 rotating film feeding means engaging said film between said first named end of 15 said loop and said holding means.

10. In kinetographic apparatus, the combination with a looped film, of film holding means with which one end of the loop communicates, a frame movable laterally with respect to said means and engaging said film at the other end of the loop, film feeding 20 means engaging said film between said first named end of said loop and said holding means, and means intermittently feeding 25 said film longitudinally with respect to said frame.

11. In kinetographic apparatus, the combination with a looped film, of film holding means with which one end of the loop communicates, a frame movable laterally with respect to said means and engaging said film at the other end of the loop, film feeding 30 means engaging said film between said first named end of said loop and said holding means, and means intermittently feeding 35 said film longitudinally with respect to said frame and movable laterally with said frame.

12. In kinetographic apparatus, the combination with a looped film, of film holding means with which one end of the loop communicates, a frame movable laterally with respect to said means and engaging said film at the other end of the loop, and means 40 movable laterally with said frame for feeding 45 said film longitudinally.

13. In kinetographic apparatus, the combination with a looped film, of film holding means with which one end of the loop communicates, a frame movable laterally with respect to said means and engaging said film at the other end of the loop, and means 50 movable laterally with said frame for intermittently feeding said film longitudinally.

55 14. In kinetographic apparatus, the combination with film storage and film receiving means, of a frame movable laterally with respect to said means, and a film moved laterally by said frame and looped on opposite 60 sides of said frame between said frame and said storage and receiving means.

15. In kinetographic apparatus, the combination with film storage and film receiving means, of a frame movable laterally with respect to said means, a film moved laterally

by said frame and looped on opposite sides of said frame between said frame and said storage and receiving means, and means for feeding said film longitudinally between said loops.

70 16. In kinetographic apparatus, the combination with film storage and film receiving means, of a frame movable laterally with respect to said means, a film moved laterally by said frame and looped on opposite sides of said frame between said frame and said storage and receiving means, and means for intermittently feeding said film longitudinally between said loops.

17. In kinetographic apparatus, the combination with film storage and film receiving means, of a frame movable laterally with respect to said means, a film moved laterally by said frame and looped on opposite sides of said frame between said frame and said storage and receiving means, means for feeding said film longitudinally between said loops, means for feeding said film from said storage means to one of said loops, and means for feeding said film from the other of said loops to said receiving means.

80 18. In kinetographic apparatus, the combination with film storage and film receiving means, of a frame movable laterally with respect to said means, a film moved laterally by said frame and looped on opposite sides of said frame between said frame and said storage and receiving means, means for feeding said film longitudinally between said loops, means for continuously feeding said 95 film from said storage means to one of said loops, and means for continuously feeding said film from the other of said loops to said receiving means.

19. In kinetographic apparatus, the combination with film storage and film receiving means, of a frame movable laterally with respect to said means, a film moved laterally by said frame and looped on opposite sides of said frame between said frame and said storage and receiving means, means for intermittently feeding said film longitudinally between said loops, means for feeding said film from said storage means to one of said loops, and means for feeding said film from the other of said loops to said receiving means.

105 20. In kinetographic apparatus, the combination with film storage and film receiving means, of a frame movable laterally with respect to said means, a film moved laterally by said frame and looped on opposite sides of said frame between said frame and said storage and receiving means, means for intermittently feeding said film longitudinally 110 between said loops, means for continuously feeding said film from said storage means to one of said loops, and means for continuously feeding said film from the other of said loops to said receiving means.

21. In kinetographic apparatus, the combination with film storage and film receiving means, of a frame movable laterally with respect to said means, a film moved laterally by said frame and looped on opposite sides of said frame between said frame and said storage and receiving means, means movable with said frame for intermittently feeding said film longitudinally from one of said loops toward the other of said loops, and means for imparting a plurality of lateral step movements to said frame and thereafter a movement to said film feeding means. 70
22. In kinetographic apparatus, the combination with film storage and film receiving means, of a frame movable laterally with respect to said means, a film moved laterally by said frame and looped on opposite sides of said frame between said frame and said storage and receiving means, means movable with said frame for intermittently feeding said film longitudinally from one of said loops toward the other of said loops, means for imparting a plurality of lateral step movements to said frame and thereafter a movement to said film feeding means, and film feeding means intervening between said loops and said storage and receiving means. 75
23. In kinetographic apparatus, the combination with film storage and film receiving means, of a frame movable laterally with respect to said means, a film moved laterally by said frame and looped on opposite sides of said frame between said frame and said storage and receiving means, means movable with said frame for intermittently feeding said film longitudinally from one of said loops toward the other of said loops, means for imparting a plurality of lateral step movements to said frame and thereafter a movement to said film feeding means, and continuously rotating film feeding means intervening between said loops and said storage and receiving means. 80
24. In kinetographic apparatus, the combination with film storage and receiving means, of an intermittently rotating film feed sprocket moving intermittently laterally with respect to said means, and a film engaging with said sprocket and looped between said sprocket and said means. 85
25. The combination with a film frame, of a pressure plate, an arm to which said pressure plate is pivoted, and a pivotal connection for said arm upon said frame, said pivotal connection being disposed to one side of the path of the film and parallel to direction of film movement. 90
26. The combination with a film guiding frame, of a pressure plate, an arm to which said pressure plate is pivoted, a pivotal connection for said arm upon said frame, and means exerting pressure on said arm to hold said pressure plate against the film, said arm swingable upon said pivotal connection with respect to said pressure exerting means, whereby said pressure exerting means exerts pressure on different parts of said arm to hold said pressure plate in retracted and operative positions respectively. 95
27. In apparatus of the character described a film having transverse rows of picture units, a frame guiding said film, apertures disposed side by side in said frame, ribs on said frame forming divisions between said apertures, and a pressure plate having similar apertures and ribs registering with said first named apertures and ribs. 100
28. In apparatus of the character described a film having transverse rows of picture units, of a transversely movable frame guiding said film, a member on which said frame has a sliding bearing, a plate engaging said member and movable transversely with said frame, means on said frame thrusting said plate against said member, said bearing being cut away at its region opposite said plate. 105
29. In kinetographic apparatus, the combination with a looped film, of film holding means with which one end of the loop communicates, and film engaging sprockets movable laterally with respect to said means and between which said film is held taut. 110
30. In kinetographic apparatus, the combination with a looped film, of film holding means with which one end of the loop communicates, film engaging sprockets movable laterally with respect to said means and between which said film is held taut, and means for intermittently actuating said sprockets laterally. 115
31. In kinetographic apparatus, the combination with a looped film, of film holding means with which one end of the loop communicates, film engaging sprockets movable laterally with respect to said means and between which said film is held taut, and means for intermittently rotating one of said sprockets. 120
32. In kinetographic apparatus, the combination with a looped film, of film holding means with which one end of the loop communicates, film engaging sprockets movable laterally with respect to said means and between which said film is held taut, and means for intermittently rotating one of said sprockets, the other of said sprockets being driven by said first sprocket through said film. 125
33. In kinetographic apparatus, the combination with a looped film, of film holding means with which one end of the loop communicates, film engaging sprockets movable laterally with respect to said means and between which said film is held taut, means for intermittently rotating one of said sprockets, the other of said sprockets being driven by said first sprocket through said film, and 130

means opposing the movement of said other sprocket.

34. In kinetographic apparatus, the combination with a film reel, of an intermittently rotating film feed sprocket movable laterally with respect to said reel, and a film engaged by said sprocket and looped between said sprocket and said reel.

35. In kinetographic apparatus, the combination with a film reel, of a continuously rotating film feed sprocket, an intermittently rotating sprocket movable laterally with respect to said first named sprocket, and a film engaged by said sprockets and looped between them.

36. In kinetographic apparatus, the combination with film engaging means, of film feeding means movable laterally with respect to said film engaging means and a film engaged by said film engaging means and looped between the same and said film feeding means, whereby the film loop is deflected laterally during lateral movement of said film feeding means.

37. In kinetographic apparatus, the combination with film engaging means, of means for moving a film laterally with respect to said means and feeding said film longitudinally after completion of lateral movement, and a film engaged by said first named means and looped between the same and said second named means.

38. In kinetographic apparatus, the com-

bination with film engaging means, of a film engaging sprocket movable laterally with respect to said means, and a film engaged by said means and looped between the same and said sprocket.

39. In kinetographic apparatus, the combination with film engaging means, of a film engaging sprocket movable laterally with respect to said means, a film engaged by said means and looped between the same and said sprocket, and means for intermittently moving said sprocket laterally and for rotating said sprocket after completion of lateral movement, said film having picture units thereon disposed in transverse rows.

40. In kinetographic apparatus, the combination with film engaging means, of a member movable laterally with respect to said means, and a film engaged by said means and looped between the same and said laterally movable member.

41. In kinetographic apparatus, the combination with film engaging means, of a film, means movable laterally with respect to said first named means for feeding said film longitudinally, said film engaged by said first named means and looped between the same and said second named means.

In testimony whereof we have hereunto affixed our signatures this 19th day of April, 1915.

RICHARD F. PIETZSCH.
ROBERT P. NICHOLS.
